ROTARY SIREN

Ernest Stuart Russell, Wraysbury, England

Application October 7, 1948, Serial No. 53,173
In Great Britain January 22, 1948

2 Claims. (Cl. 177—7)

1

This invention is designed to facilitate the operation of sirens of the rotary type. Such sirens commonly have a rotor with substantially radial blades and a ported rim so arranged as to create by centrifugal force a pressure of air against a stator having the same number of ports. The rotation of the rotor in the stator has the effect of alternately opening and closing the stator ports to the egress of air and so creates a noise varying in frequency with the number of ports and the speed of rotation.

The acceleration and deceleration of the rotors of such sirens produce wailing notes such as adopted for air raid warnings and since the times of acceleration and deceleration are long due to the high inertia of the electrical and sound rotors such sirens cannot be used to give sharp and distinct signals or signals of short duration.

This difficulty has been partially overcome in sirens constructed by the applicant in which the air intake of a standard siren is fitted with a mechanically or electrically operated valve or shutter.

By allowing the siren to rotate continuously whilst the shutter is opened and closed in a prearranged time sequence it is possible to obtain distinctive signals. Shutters on the discharge side of the stator have also been tried.

It has also been proposed in United States Patent No. 2,535,520, granted to me December 26, 1950, to fit a cover which envelops both the suction and discharge portions of the siren so as to prevent ingress of air from and egress to outside the cover when this is pressed against a flange or the equivalent on the siren stator. Such a cover may be arranged to obstruct entirely the inlet to the rotor when the cover is sealed on to the stator so as to prevent any internal circulation of air except that within the actual stator. Further, the rotor shaft may be made hollow so that an operating rod supported on external bearings may pass through it without touching it. This rod is used to apply manual or electromagnetic pressure to the cover, to open or close it.

For the purpose of operating the shutters, valves or covers of rotary sirens, it has been the usual practice to employ direct manual power by means of a system of levers operated by a lanyard, or an electromagnet. In the case of sirens requiring any considerable effort to open or close the shutter or cover it has been found inconvenient to use manual power and the size and cost of an electromagnet capable of exerting the necessary power have been so great as to make this system undesirable.

The present invention provides a means of

2

furnishing and applying the necessary power to operate rotary sirens of all the above mentioned and similar types in a convenient manner which combines ease and speed of operation with moderate cost and without the necessity for undue occupation of space by the operating mechanism.

This is accomplished by connecting the shutter or cover to fluid pressure operated actuating means and utilising the motor which drives the siren rotor also to drive means for supplying fluid under pressure to the actuation means.

Accordingly, one important feature of the invention lies in the application of fluid pressure to actuate the operating means of such sirens, irrespective of the source from which the pressure fluid is derived, though it will often be convenient to drive a pressure pump or the equivalent from the motor which drives the siren and so make the apparatus substantially self-contained. When the siren is driven electrically it is also often convenient to control electrically the application of the pressure to the actuating means.

An important part of the invention lies in the control of the actuating means by two pressure relief devices, one becoming operative automatically when a given movement of the siren controlling means is exceeded, so limiting the travel of the siren operating valve, shutter, cover or the like, and the other being valve means closable against the pressure of the fluid to cause its application to the actuating means and consequent initiation of a sound signal and openable to relieve the pressure (by exhaust to atmosphere bypassing or otherwise) and so to cause the signal to be cut off. The valve means may take the form of an electrically (conveniently solenoid) operated valve, enabling push button or similar simple electrical control of the whole apparatus to be used.

The invention thus embodies several parts or aspects, those for which patent protection is desired being embodied in the apparatus hereinafter described and delimited by the claims.

A typical form of the invention is shown by way of example by the accompanying drawing which is a central vertical section of an electrically driven siren using a cover to control the initiation and cutting off of signals.

The outer case 1 contains an electric motor consisting of field yoke 2 and rotor 3 mounted upon bearing assemblies 4 and 5. Hollow shaft 6 carries sound rotor 7 running in stator 8. The cover 9 having a bush 10 is slidably mounted upon pillar 11 which forms part of stator cover 12 containing the suction intake which is normally closed by valve disc 13. The opening and

closing of the cover 9 and valve disc 13 to enable the giving of sharp and distinct signals as described in the United States Patent No. 2,535,520 is accomplished by the vertical movement of push rod 14. The upward movement of this rod is made by fluid pressure displacing piston 15 in cylinder 16. A hollow shaft 27 carries a centrifugal pump impeller 17 at its lower extremity. This impeller running within the pump casing 18 draws oil or other liquid (the liquid level in the fluid reservoir 29 formed by the bottom of the outer case 1 being indicated at 28) through the suction intake 19 and discharges it under pressure through a discharge orifice 20 and pipe 21 leading to the lower part of cylinder 16. A valve 22 which can be held closed by the energising of electro-magnet 23 which holds armature 24 against valve 22 will prevent the escape of the oil and will allow a pressure to build up in the cylinder whilst rotor 3 is turning. This pressure will cause piston 15 to rise and this in its turn will cause cover 9 and valve 13 to open by means of push rod 14. When cover 9 has reached the limit of its desirable stroke, piston 15 will start to uncover exhaust ports 25 and there will be a bleeding of the pressure so as to establish an equilibrium between the pressure applied to piston 15 and the gravity and suction pulls upon cover 9 tending to oppose this pressure.

When it is desired to close cover 9 and valve 13 the electrical circuit supplying electromagnet 23 is opened. This allows the fluid pressure to open valve 22 with the result that the pressure applied to piston 15 is insufficient to support the cover 9 which closes rapidly under the influence of the gravity and suction pulls.

Whilst the electric motor is running it is possible to make any number or preconceived sequence of sharp and distinct signals by opening and closing the electrical circuit to electromagnet 23.

The following considerations may be helpful to a proper understanding of the nature and merits of the invention. In order to make push button or like operation of the means for actuating the cover or other signal control means of the siren, electro-magnetic devices are suitable only for relatively small sirens. In trying to devise means to utilize a rotary movement, preferably the power of the electric motor of the siren, it appeared necessary to introduce between the electric motor shaft and the cover such a series of reduction gears, clutches, cams and the like, as to make the whole apparatus costly to manufacture, difficult to maintain, and eminently unreliable in service. The same thing applied to the instantaneous releasing of the cover upon the releasing of the operating push button. Use of electromagnets is permissible in very small sizes of sirens, but when any large amount of power is to be exerted these become too large and take too much power. The dissipation of the heat from these also becomes a great problem. It should be remembered that the amount of power to be exerted for the opening of the cover is not only the amount of power necessary to overcome the weight of the mass of the cover but also the power required to oppose the suction pull on the cover at the suction intake of the fan. This is considerably in excess of the gravity pull. It must also be borne in mind that the effective pull of a solenoid varies as the square of the dimension of the air gap and that initial closing speed is very slow, whereas in the case of sirens, and particularly marine sirens, it is the initial

movement which should be quick in order that in times of danger a sound signal may be given quickly. The use of fluid pressure to raise the cover has provided the solution to all these problems and it has been found that even from a standing start the opening of the cover is almost instantaneous because the centrifugal pump can be designed to give a pressure sufficient to raise the cover even when it is running at a low speed.

When the cover has reached the limit of its stroke the pump is automatically unloaded by the bleeding through the holes 25.

Fundamentally, I have accomplished my object with a source of fluid pressure and only two moving parts—that is to say, the piston and the electrically operated relief valve, whereas with any mechanical apparatus I should have had to use anything up to fifty or sixty parts, and the apparatus would in any case have been unsatisfactory.

The basic idea underlying the invention in its broader aspects from this point of view accordingly requires in practice any form of pressure relief device to limit the travel of the control device; any form of quick pressure application and instant relief device to initiate and terminate the signal; and any source of fluid pressure, whether a pump embodied in the siren casing, an external pump assembly, fluid pressure from available containers or reservoirs, or any other appropriate source.

I claim:

1. A rotary siren of the type having a power driven rotor and including operating means to free and obturate the air flow through the siren to initiate and cut off signals characterised by the provision of a fluid reservoir, a pressure cylinder and piston, a pump drawing fluid from the said reservoir and supplying it under pressure to the pressure cylinder, an actuating member operatively connecting the said piston to actuate the means operating to free the air flow through the siren and initiate signals, valve means automatically relieving the pressure in the cylinder after a given movement of the piston and a control valve operable to maintain or relieve at will the working pressure in the said cylinder.

2. A rotary siren including movable obturators which free and obturate the flow of air through the siren, fluid pressure operable means operatively connected with said obturators to move them to free the air flow, said fluid pressure operable means including a casing having bleeder openings therein and a piston operable in said casing, said openings bleeding the fluid subject to a predetermined amount of movement of said piston, and a pressure relief valve to relieve the working pressure and enable the obturators to return to the position where the air flow through the siren is obturated.
